DRIVING MEANS FOR SLICING MACHINES

Harold C. Grove, Charlotte, N. C.

Application January 5, 1953, Serial No. 329,879

9 Claims. (Cl. 146—102)

1

This invention relates to slicing machines and the like of the gravity-feed type and, more especially, to an improved detachable or disengagable means for driving the reciprocating table or carriage of such machines upon which the article to be operated upon is supported and by which the article is moved into and out of engagement with a power driven knife.

It is the primary object of this invention to provide an improved conversion driving unit for machines of the aforementioned type which may be readily mounted on existing slicing machines; which is compact, light in weight, and may be conveniently operated.

It is another object of this invention to provide a novel construction and arrangement of parts comprising power operated mechanisms for reciprocating the table or carriage of a slicing machine with means for quickly engaging and disengaging the power operated mechanisms relative to the table, article support or carriage to permit free operation thereof by hand, if so desired.

More specifically, it is still another object of this invention to provide a conversion driving unit of the character described, wherein a driven slicing knife or blade is provided, which comprises a pair of closely spaced parallel endless belts or sprocket chains with driving connections between the driven slicing blade or knife and the endless belts or sprocket chains. A shaft is supported at opposite ends thereof by said endless belts or chains and extends between adjacent belts and has a carriage propelling thrust rod or pin thereon which projects upwardly and is slidably mounted in the lower portion of the carriage, support or table, the pin being of such length that it will remain in engagement with the carriage throughout movement of the endless belts or chains as they pass between and around their pulleys or sprocket wheels. In so doing, the endless belts or sprocket chains impart reciprocatory movement to the carriage.

Also, two forms of means for throwing the driving means for the reciprocating table or carriage out of operative relation with the reciprocating table or carriage are embodied in this application. One form of means for throwing the driving means out of operative relation with the table or carriage includes a clutch means interposed in the driving means for the endless belts or sprocket chains with manual means for shifting the clutch into and out of operation.

The other means includes an auxiliary carriage spaced immediately below the article sup-

2

porting carriage or table and in which said thrust rod or pin has vertical reciprocatory movement as it imparts movement thereto. A manually shiftable means carried by the article support or carriage may be moved into and out of engagement with a projection or pin on the auxiliary carriage whereby, when the shiftable means carried by the article support or carriage is moved out of operative relation with the auxiliary carriage, the auxiliary carriage may continue to reciprocate as said vertically reciprocable pin moves in engagement therewith, as it is driven by said endless belts or sprocket chains and to thereby permit free operation of the article carriage or support by hand, if so desired.

This application is a continuation-in-part of my co-pending application entitled Manual and Automatic Conversion Driving Unit for Slicing Machine, filed February 23, 1952, and bears Serial Number 272,948.

Some of the objects of the invention having been stated, other objects will appear as the description proceeds, when taken in connection with the accompanying drawings, in which—

25 Figure 1 is an isometric view of a gravity-feed type of slicing machine;

Figure 2 is an enlarged end elevation looking at the opposite end of the slicing machine from that shown in Figure 1;

30 Figure 3 is an enlarged longitudinal substantial vertical sectional view taken substantially along the line 3—3 in Figure 2 and showing one form of the improved means for imparting reciprocating movement to the article support or carriage;

Figure 4 is a sectional plan view taken substantially along the line 4—4 in Figure 3, with parts broken away and with other parts in section;

35 Figure 5 is an enlarged vertical sectional view taken substantially along the line 5—5 in Figure 3;

Figure 6 is an enlarged vertical sectional view taken substantially along the line 6—6 in Figure 3 and wherein the frame of the machine is disposed at an angle for purposes of clarity;

Figure 7 is an enlarged fragmentary detailed view with parts in section, taken substantially along the line 7—7 in Figure 6 and showing, particularly, the manner in which the shifting yoke for the clutch is supported;

Figure 8 is a fragmentary isometric view, with parts in section and other parts broken away, looking substantially in the direction of the 55 arrow 8 in the central left-hand portion of

Figure 6 and showing the manner in which the vertically reciprocable carriage thrust shaft or pin is supported by the endless belts or chains;

Figure 9 is an enlarged vertical sectional view similar to Figure 3, but with the left-hand portion thereof broken away and showing another form of means for throwing the driving means for the reciprocating article carriage out of operative relation with the article carriage to permit free operation thereof by hand;

Figure 10 is a fragmentary substantially vertical sectional view taken substantially along the line 10—10 in Figure 9;

Figure 11 is another vertical sectional view taken substantially along the line 11—11 in Figure 10.

Referring more specifically to the drawings, the conversion driving unit or improved driving means for the article carriage or support is shown in association with a slicing machine of a type manufactured by American Slicing Machine Company, Chicago, Illinois, and wherein, heretofore, the carriage of the machine has been reciprocated solely by hand. Since the primary elements of a slicing machine with which the present invention may be associated are a driven cutter blade and the horizontally movable carriage, it will be apparent that the present invention may be used in association with many other types of slicing machines, the slicing machine in the drawings being shown by way of illustration only. However, in order that the invention may be clearly understood, a description will first be given of the slicing machine.

The slicing machine comprises a cast frame or base broadly designated at 20 which is substantially inverted U-shaped in cross-section and has integrally cast side walls 21 and 22 and end walls 23 and 24, which may be termed as front and rear end walls, respectively. The upper edges of the side walls 21 and 22 and the end walls 23 and 24 are connected to the edges of an angularly disposed top wall 25 which only partially encloses the upper portion of the base 20 and is provided with a longitudinally extending opening or slot 26 therein.

The base or cast frame 20 is provided with a plurality of foot pads 30 at the corners thereof on which the cast frame or base 20 is supported. The upper edges of the end walls 23 and 24 of the cast frame or base 20 have suitable primary or article carriage guide supports 31 and 32 suitably secured thereto in which opposite ends of a pair of transversely spaced longitudinally extending guide bars or rods 33 and 34 are supported.

It will be noted that the guide bars 33 and 34 are disposed at different levels corresponding to the angularity of the upper wall 25 of the base 20. However, these guide bars 33 and 34 are shown disposed at the same level in Figure 6, since the machine is tilted at an angle for purposes of clarity and to correspond to the line 6—6 along which Figure 6 is taken in Figure 3. It will be noted that the upper edges of the supports 31 and 32 are curved and support opposite ends of a conventional shield or guard 35.

A conventional primary or article carriage, table or support, broadly designated at 36, is mounted for longitudinal sliding movement on the guide bars 33 and 34 and, in this instance, the carriage 36 is shown disposed at an angle transversely of the cast frame or base 20 and is therefore commonly known as a gravity-feed carriage. The carriage 36 is preferably of cast

construction and the front and rear walls thereof are provided with corresponding openings 37 and 40 through which the guide bars 33 and 34 and the shield 35 extend.

The carriage 36 is of a substantially greater width than the shield 35 and opposite side portions thereof, which define the openings 37 and 40, are bridged by a transverse guide block 41 (Figures 2, 3 and 6) which is slidably penetrated by the guide bars 33 and 34, thus facilitating movement of the carriage 36 longitudinally of said bars 33 and 34. The carriage 36 may be of conventional or any other desired construction and shape and a detailed description thereof is thus deemed unnecessary. However, it might be stated that the carriage 36 has a substantially V-shaped article or material support 43 thereon for supporting the material to be sliced, such as meat or the like.

The carriage 36 also has a forwardly extending projection 44 thereon in which the lower end of an upright handle 45 is suitably secured. The handle 45 is adapted to be grasped by an operator to facilitate reciprocating the carriage 36 by hand longitudinally on said guide bars 33 and 34, when desired.

The frame or base 20 also has a conventional blade housing 46 thereon in which a circular blade or cutting knife 47 is partially disposed. This blade 47 is disposed adjacent the carriage 36 and is of substantially concavo-convex configuration. It will be observed that the housing 46 is closed by a rear guide plate 50 which is so formed that the cutting edge of the blade 47 projects outwardly at the front edge of the guide plate 50 and an adjustable front guide plate 51 is also disposed in substantially parallel relation to the guide plate 50.

Thus, as the carriage 36 is moved forwardly from adjacent the end wall 23 to the end wall 24 of the base 20, the material to be severed is supported upon the article supporting member 43 and slides against the guide plate 51 and, as the slice is removed therefrom by the blade 47, the slice passes back of the blade 47 relative to the side wall 21 of the base 20 and the material then slides against the plate 50.

The blade 47 is driven in a conventional manner by means of a grooved pulley 52 fixed to the outer surface thereof relative to the guide plate 50 and which is engaged by an endless belt 53 also mounted on a multi-grooved pulley 54. The multi-grooved pulley 54 is fixed on the shaft 55 of an electric motor 56 suitably supported by the frame 20 and having wires 57 and 58 extending therefrom to a suitable source of electrical energy, not shown. The base 20 also has a suitable platform 61 secured thereto onto which the slices of meat or the like fall as they are severed by the blade 47.

It will be observed in Figure 4 that the front article guide plate 51 is suitably secured to a bracket 62 fixed on corresponding ends of transverse angularly disposed guide rods or bars 63 and 64. The guide rods 63 and 64 are mounted for lateral sliding movement relative to the guide bars 33 and 34 in the side wall 22 and, also, the guide rod 64 spans the distance between the side walls 22 and 21 and is slidably mounted in the side wall 21. A follower supporting bracket 65 is adjustably secured intermediate the ends of the shaft or guide bar 64 and has one end of a tension spring 66 connected thereto. The other end of the tension spring is suitably connected 75 to the inner surface of the side wall 22.

Thus, the tension spring 66 normally urges the front article guide plate 51 outwardly or away from the observer in Figure 3 and serves as a counter-balancing means for the article guide plate 51. The bracket 65 has a pair of spaced cam followers 70 and 71 thereon which engage substantially diametrically opposed surfaces of respective cam wheels 72 and 73 fixed on one end of a relatively short longitudinally extending shaft 74 (Figure 1). The shaft 74 is rotatably supported in the end wall 23 and has a control knob 75 fixed on the outer end thereof which is shown in partially exploded relation to the end wall 23 in Figure 1 to illustrate suitable graduations thereon adjacent which an indicating mark 76 is provided on the front wall 23.

The purpose of the graduations on the control knob 75 is to facilitate determining the spacing between the cutter blade 47 and the front article guide plate 51. In other words, by rotating the control knob 75 in one direction, the cam wheels 72 and 73 cause the shaft or guide bar 64 to move transversely in one direction to thus move the article guide plate 51 outwardly relative to the blade 47 for increasing the thickness of the slices to be severed from the cut of meat or the like. On the other hand, upon rotating the knob 75 in the other direction, the article guide plate 51 is caused to move closer to the blade 47 (Figure 1) for cutting relatively thinner slices.

The means for varying the position of the front article guide plate 51 relative to the blade 47 does not constitute a part of the present invention, but is merely shown to illustrate that the present invention may be used in association therewith and is so designed that it will not interfere with the operation of said means for varying the position of the article guide plate 51.

The parts heretofore described are conventional parts of a slicing machine and do not, necessarily, constitute parts of the present invention, the slicing machine described merely being a preferred type of machine with which the present invention is adapted to be associated.

Now, in order to facilitate either manual or automatic reciprocation of the carriage 36, as desired, I have provided a unique form of driving means for the carriage wherein two forms of means are disclosed for throwing the driving means out of operative relation with the article carriage or support to permit free operation thereof by hand if so desired. To this end, in the first form of the invention there is provided an elongated gear box or driving unit housing, broadly designated at 80 which is spaced beneath and extends in substantially parallel relation to the guide bars 33 and 34 for the carriage 36. The gear box or driving unit housing 80 is preferably of cast construction and comprises a bottom wall 81, side walls 82 and 83 and end walls 84 and 85.

A top wall or cover 86 is suitably secured to the upper edges of the walls 82 to 85, inclusive, as by screws 87 (Figures 4, 5 and 6). The cover or top wall 86 has a narrow longitudinally extending slot 90 in the center thereof and, since the top wall or cover 86 extends at an angle in substantially parallel relation to the top wall 26 of the cast base or frame 20, a suitable shield or lubricant retainer 91 is suitably secured to, and projects upwardly from, the top wall or cover 86 and is disposed immediately adjacent the lower wall of the slot 90. It is to be under-

stood that a suitable lubricant may be contained in the housing 80.

The housing 80 is suitably supported by means of brackets 93 and 94 (Figures 2, 3 and 4) which are suitably secured to the outer surfaces of the end walls 84 and 85 and extend outwardly therefrom. The outer or distal ends of the brackets 93 and 94 are suitably removably secured to the proximal surfaces of the end of walls 23 and 24 of the cast frame or base 20, as by bolts 96. It will be noted that the bracket 93 is so formed that it passes beneath, and thus clears, the cam wheels 72 and 73. Disposed within the housing 80 are respective first and second endless belts or sprocket chains 100 and 101 which extend in closely spaced parallel relationship to each other.

The endless belts or sprocket chains 100 and 101 are mounted on respective pairs of pulleys or sprocket wheels 102, 103 and 104, 105 rotatably mounted on respective shoulder bolts 106 to 109, inclusive. The shoulder bolts 106 and 107 are carried by the side wall 82 and the shoulder bolts 108 and 109 are carried by the side wall 83 of the housing 80. The proximal edges of the sprocket chains or endless belts 100 and 101 have opposite ends of a pivot shaft 112 suitably secured thereto and, in this instance, it will be observed in Figure 8 that the opposite ends of the pivot shaft 112 are suitably secured to the proximal sides of the medial portions of adjacent links of the sprocket chains 100 and 101.

The enlarged lower end 113 of a vertically reciprocable carriage propelling thrust pin or shaft 114 is pivotally supported on the pivot shaft 112 and extends upwardly therefrom through slot 90 in the cover 86 and slidably penetrates a guide bushing 115 carried by a guide block 116 suitably secured to, or integral with, the medial portion of the transverse guide block 41 of the carriage 36. The guide block 41 of the carriage 36 also has an opening 117 therein through which the upper portion of the carriage thrust pin or shaft 114 extends as it moves with the upper reaches of the endless belts or sprocket chains 100 and 101.

It is evident that the particular manner in which the upper portion of the vertically reciprocable carriage thrust shaft or pin 114 is connected to the transverse guide block 41 of the article carriage 36 may be varied somewhat without departing from the spirit of the invention. For example, the transverse block 41 may be especially constructed with a boss depending therefrom in lieu of the bushing 115 and in which the pin 114 may have longitudinal reciprocatory movement.

The sprocket wheels or pulleys 102 and 104 are suitably secured to, or may be integral with, hub portions of respective gears 120 and 121 also rotatably mounted on the respective shoulder bolts 106 and 108. The gears 120 and 121 mesh with respective pinions or gears 122 and 123 fixed on a common transverse shaft 124 rotatably mounted in the side walls 82 and 83 of the housing 80 (Figures 3, 4 and 6). One end of the shaft 124 has an axially movable clutch member 125 slidably mounted thereon, which is provided with a longitudinal slot 126 therein in which a pin or key 127 is disposed. The pin or key 127 is suitably secured to the shaft 124. Thus, the pin or key 127 permits longitudinal movement of the movable clutch member 125, but prevents relative rotational movement between the clutch member 125 and the shaft 124.

The clutch member 125 is normally urged into

engagement with a mating clutch member 130 by any suitable means such as a compression spring 131 which surrounds the shaft 124 and opposite ends of which bear against the movable clutch member 125 and the outer surface of the wall 83 of the housing 80. The clutch member 125 has a peripheral groove 132 therein which is slidably engaged by suitable diametrically opposed projections or arms 133 and 134 of a yoke member broadly designated at 140 (Figures 4, 6 and 7).

The yoke member 140 is fixed on one end of a shifting lever 141 which is pivoted, as at 142, on the side wall 83 of housing 80 and then extends downwardly at an angle and then forwardly and has an up-turned portion 141a (Figures 1, 4 and 6) on the front end thereof which is adapted to be grasped by an operator for imparting movement to. It will be observed in Figures 1 and 6 that the lower edge of the front wall 23 of casing or frame 21 has a pair of notches 143 and 144 therein and in either of which the shifting lever 141 is adapted to be positioned.

The wall 23 of the frame 21 has the word "Stop" disposed above the notch 143 and the words "In Gear" above the notch 144 to thereby indicate whether the clutch members 125 and 130 are in engagement with each other. It might be stated that the lever 141 is made of a material sufficiently flexible to be biased downwardly relative to pivot 142 when it is shifted from the "Stop" position to the "In Gear" position.

The proximal surfaces of the clutch members 125 and 130 have mating teeth thereon as best shown in Figure 4. The outer end of the shaft 124 terminates short of the toothed end of the movable clutch member 125, when said clutch member is positioned out of engagement with the mating clutch member 130, and the proximal end of a drive shaft 146 (Figure 6) is mounted for rotation in the outer end of the movable clutch member 125. The clutch member 130 is suitably fixed on the drive shaft 146 and, thus, remains in fixed relation to the shaft 146.

The end of shaft 146 remote from the clutch members 125 and 130 is rotatably supported in a suitable bearing block 147 carried by the frame 20 and adjacent which a grooved pulley 150 is fixed on the shaft 146. The grooved pulley 150 is engaged by an endless belt 151 which extends upwardly in Figures 3 and 6 and is mounted on the multi-grooved pulley 54 heretofore described. Thus, the motor 56 imparts continuous rotation to the blade 47, the shaft 146 and clutch member 130. However, when the movable clutch member 125 occupies the position shown in Figure 6, the carriage 36 may be manually reciprocated independently of the driving means therefor, including the shaft 146; although manual reciprocation of the article carriage 36 will impart corresponding movement to the endless belts or chains 100 and 101, the sprocket wheels or pulleys 102 to 105, the gears 120 to 123, inclusive, the shaft 124 and the clutch member 125. Manual reciprocation of the carriage 36 may be desirable when only a few slices of meat or the like are desired; or, for example, in slicing large cuts of meat such as luncheon meat, bacon, cooked ham, large boneless hams, and the like.

On the other hand, if a large number of slices are to be cut from either large or small cuts of meat or the like, the operator may desire that the carriage 36 reciprocates automatically, in which instance, it is only necessary for the operator to move the shifting lever 141 in engagement

5 with the notch 144 in the lower edge of the wall 23 of the casing 21. In so doing, the movable clutch member 125 is shifted from the position shown in Figure 6 into engagement with the driving clutch member 130 as shown in Figure 4; and, since the shaft 146 is constantly driven as the blade 47 is driven, it is evident that this will cause the shaft 124 to rotate and will thereby impart movement to the endless belts or sprocket chains 100 and 101.

Accordingly, the upper reaches of the endless belts or sprocket chains 100 and 101 will move forwardly as the lower reaches thereof move in the opposite direction. The length of the vertically reciprocable thrust pin 114 is such that it will remain in engagement with the bushing 115 regardless of whether the pivot pin 112 therefor is moving with the upper reaches of the sprocket chains 100 and 101 or the lower reaches thereof and, accordingly, the sprocket chains 100 and 101 will transmit reciprocatory movement to the article carriage 36.

It is thus seen that I have provided a novel means for imparting reciprocatory movement to the article carriage 36 of the slicing machine and wherein means are provided whereby the power operating mechanism for reciprocating the table or article carriage may be thrown out of operative relation with the table or article carriage to permit free operation thereof by hand, if so desired.

Second form of clutch means for throwing the driving mechanism for reciprocating the carriage into and out of operative relation with the carriage

As heretofore stated, when the movable clutch member 125 is disengaged from the driving clutch member 130, it is necessary for the operator to impart movement to the sprocket chains 100 and 101, the sprocket wheels 102 to 105, inclusive, the gears 120 to 123, inclusive, the shaft 124 and the movable clutch member 125, when manually imparting reciprocatory movement to the carriage 36.

Now, in order to permit relative movement between the carriage and the endless belts or chains 100 and 101 and the movable parts connected thereto, I have provided a second form of means whereby the power operated mechanism for reciprocating the table or article carriage may be thrown out of operative relation with the table or article carriage to permit free operation thereof by hand, when desired, as shown in Figures 9, 10 and 11.

Since the conventional parts of the slicing machine shown in Figures 9, 10 and 11 are identical to the parts shown in Figures 1 to 8, inclusive, and, also, since many of the parts of the improved driving mechanism shown in Figures 9, 10 and 11 are identical to those shown in Figures 1 to 8, inclusive, only those parts shown in Figures 9, 10 and 11 which differ from the parts shown in Figures 1 to 8, inclusive will be described in detail and the remaining parts shall bear the same reference characters as similar parts shown in Figures 1 to 8, inclusive; with the prime notation added.

In the form of carriage drive detaching means shown in Figures 9, 10 and 11, the reciprocable carriage driving shaft 114' is preferable relatively shorter than the original shaft 114, assuming the housing 80' to be spaced substantially the same distance below the guide block 41'

as the housing 80 is spaced below the guide block 41.

The thrust pin or vertical reciprocable shaft 114' has substantially vertical or longitudinal sliding movement in a bushing or guide member 160 which partially extends through the slot 90' in the top wall or cover 86' of the housing 80'. The upper end of the bushing or guide member 160 is fixed in an auxiliary carriage 161 spaced below the guide block 41' of the article carriage 36' and being mounted for movement parallel to the guide block 41' on auxiliary carriage guide rods or bars 162 and 163. Opposite ends of the auxiliary carriage guide bars or rods 162 and 163 are suitably secured in extensions 164 and 165 projecting upwardly from, and being suitably secured to or integral with, the end walls 84' and 85' of the housing 80'.

The auxiliary carriage 161 has a latch or clutch pin 167 suitably secured thereto and projecting upwardly therefrom and which is preferably disposed in side by side parallel relation to the vertically reciprocable pin or shaft 114'. When it is desired to operate the table or article carriage 36' mechanically, the pin 167 is in engagement with the lower end of a vertically movable clutch dog or plunger 170 which is preferably rectangular in cross-section and is mounted for vertical sliding movement in the guide block 41' of the article carriage 36'. Of course, the vertically reciprocable clutch 170 may be circular in cross-section and suitably keyed in the guide block 41', if desired.

The lower end of the clutch dog 170 has a pair of downwardly converging tapered cam surfaces 171 and 172 thereon between which the lower end of the vertically movable dog or plunger 170 is provided with a notch or cavity 173 which is adapted to fit over the upper end of the pin 167 when it is desired to operate the table or article carriage by power. The medial portion of the vertically reciprocable plunger or clutch dog 170 has a shoulder 174 thereon which is normally urged into engagement with the upper surface of the guide block 41' of the article carriage 36' by a compression spring 175. The compression spring 175 engages the upper end of the clutch dog or plunger 170 at one end thereof and the other end thereof engages the lower surface of the top wall of an inverted substantially U-shaped or cup-shaped bracket 176 suitably secured, as by screws 177, to the upper surface of the guide block 41'.

Since the bracket 176 is supported upon the guide block 41', it is evident that a shield, such as the shield 35 in Figures 1, 2 and 3, would either have to be omitted from the form of the invention shown in Figures 9, 10 and 11 or a suitable slot would have to be provided therein to accommodate the bracket 176 and adjacent parts. Opposite sides of the inverted cup-shaped or U-shaped bracket 176 are provided with coinciding vertically extending slots 190 in which opposite end portions of a transverse pin 181 have vertical sliding movement. The pin 181 penetrates the upper portion of the plunger or clutch dog 170 and is preferably fixed therein, as by a pressed fit.

One end of the pin 81 is urged into engagement with the upper surface of an eccentric cam broadly designated at 182 fixed on a manually rotatable cam shaft 183. One end of the cam shaft 183 is rotatably supported in the bracket 176 and the other end thereof is rotatably supported in the outermost side wall of the article 75

carriage 36' relative to the blade 47'. A suitable adjusting knob 185 is fixed on the outer end of the cam shaft 183. The hub of the knob 185 and a suitable collar 186, fixed on the shaft 183, prevent endwise movement or longitudinal movement of the cam shaft 183.

It will be observed in Figure 9 that the eccentric cam 182 has a substantially radially extending portion 182a integral therewith which is provided with a concave notch or groove 182b in the outer end thereof. Thus, by rotating the cam 182 in a clockwise direction in Figure 9, it is evident that the pin 181 will be moved upwardly in engagement with the cam 182 until it rests in engagement with the notch 182b in the cam 182 and this will raise the clutch dog or vertically movable plunger 170 from the dotted line to the solid line position shown in Figure 11.

The operator may then manually reciprocate the carriage 36' without being encumbered by the parts disposed within the housing 80' and, also, the parts disposed within the housing 80' may continue to operate along with the auxiliary carriage 161. It is evident that a clutch mechanism such as that shown in the right-hand central portion of Figure 6 would not be necessary in association with the form of the invention shown in Figures 9, 10 and 11.

If it is desired to reciprocate the table or article carriage 36' by power, the cam 182 is returned to the position shown in Figure 9 to thereby permit the spring 175 to move the clutch dog or vertically reciprocable plunger 170 downwardly to the dotted line position shown in Figure 11. This may be done regardless of the relative position of the pin 167 in the auxiliary carriage 161 and even though the auxiliary carriage may be reciprocating at the time that the vertically reciprocable plunger or clutch dog 170 is permitted to move to its operative or dotted line position shown in Figure 11.

Now, assuming the auxiliary carriage 161 to be in the solid line position shown in Figure 11, and the clutch dog or vertically reciprocable plunger 170 to be in the lowered or operative position shown in dotted lines in Figure 11, as the pin 167 engages the cam surface 172, with movement thereof from right to left in Figure 11, the pin causes the clutch dog or vertically reciprocable plunger 170 to move upwardly and to then fall downwardly so the pin 167 is positioned in the cavity or notch 173 in the lower end of the vertically reciprocable plunger 170 as shown in broken lines in Figure 11 and as shown in solid lines in Figures 9 and 10. It is evident that the auxiliary carriage 161 would then impart reciprocatory movement to the article carriage 36'.

Of course, in the event that the auxiliary carriage 161 is moving from left to right in Figure 11 and is disposed to the left of the vertically reciprocable plunger or clutch dog 170 as the clutch dog 170 is moved to the broken line position shown in Figure 11, the pin 167 would engage the cam surface 171, forcing the clutch dog 170 upwardly and whereupon the clutch dog 170 would be moved downwardly by the spring 175 to the broken line position shown in Figure 11, with the pin 167 disposed in the notch 173.

In the drawings and specification there has been set forth a preferred embodiment of the invention and although specific terms are employed, they are used in a generic and descriptive sense only, and not for purposes of limitation, the

scope of the invention being defined in the claims.

I claim:

1. In a slicing machine having a frame, an article carriage for material to be sliced reciprocally mounted on said frame and a driven rotary cutter blade disposed adjacent the carriage; the combination of improved means for imparting reciprocatory movement to said article carriage comprising a pair of closely spaced parallel endless belts spaced beneath, and extending in substantially parallel relation to, the path of movement of the article carriage, a pivot shaft supported at opposite ends thereof in adjacent reaches of said pair of endless belts and spanning the distance therebetween, a carriage propelling shaft pivotally mounted adjacent its lower end on said pivot shaft, means carried by said article carriage for slidably guiding the upper portion of said propelling shaft, and a driving connection between the rotary cutter blade and said endless belts for imparting movement to the endless belts whereby said propelling shaft will move the article carriage in one direction when moving with the upper reaches of said endless belts and will move the carriage in the opposite direction when moving with the lower reaches of said endless belts.

2. In a slicing machine having a frame, an article carriage for material to be sliced reciprocally mounted on said frame and a driven rotary cutter blade disposed adjacent the carriage; the combination of a pair of closely spaced parallel endless belts spaced beneath and extending in substantially parallel relation to the path of movement of the article carriage, a pivot shaft supported at opposite ends thereof in adjacent reaches of said pair of endless belts and spanning the distance therebetween, a carriage propelling shaft pivotally mounted adjacent its lower end on said pivot shaft, means carried by said article carriage for slidably guiding the upper portion of said propelling shaft, a driving connection between the rotary cutter blade and said endless belts for imparting movement to the endless belts whereby said propelling shaft will move the article carriage in one direction when moving with the upper reaches of said endless belts and will move the carriage in the opposite direction when moving with the lower reaches of said endless belts, and manually operable means for disengaging the driving means relative to the carriage to facilitate manual reciprocation of the article carriage.

3. In a slicing machine having a frame, an article carriage reciprocally mounted on said frame and a motor; the combination of mechanism for mechanically reciprocating the article carriage, said mechanism including a pair of closely spaced parallel endless belts, means operated by the motor for driving the endless belts continuously in one direction, a propelling shaft mounted for axial sliding movement in a part of said carriage and extending laterally relative to the direction of travel of said carriage, and means carried by, and disposed between, the proximal portions of said endless belts for pivotally supporting said propelling shaft whereby movement of said belts will impart reciprocatory movement to the article carriage.

4. In a slicing machine having a frame, an article carriage reciprocally mounted on said frame and a motor; the combination of mechanism for mechanically reciprocating the article carriage including a pair of closely spaced parallel endless chains, means operated by the

motor for driving the endless chains continuously in one direction, a thrust shaft mounted for axial sliding movement in a part of said carriage and extending laterally relative to the path of movement of said carriage, and means carried by, and disposed between, the proximal portions of said endless chains for pivotally supporting said thrust shaft whereby movement of said chains will impart reciprocatory movement to the article carriage.

5. In a slicing machine having a base, an article carriage reciprocally mounted on said base and a driven rotary cutter blade disposed adjacent said article carriage; the combination of an elongated housing spaced below and disposed in substantially parallel relation to the article carriage, said housing having spaced side walls, a pair of longitudinally spaced parallel wheels carried by each of said side walls, the wheels carried by one side wall being in substantially axial alignment with the respective wheels carried by the other side wall, a pair of closely spaced substantially parallel endless belts carried by the wheels, a pivot shaft spanning the distance between, and being carried by, adjacent reaches of the endless belts, a carriage propelling thrust shaft pivotally supported on said pivot shaft, means on said carriage for slidably supporting the upper end of said thrust shaft, and a driving connection between the rotary cutter blade and at least one of the wheels on which each of the endless belts are mounted whereby said endless belts will impart reciprocatory movement to the article carriage.

6. In a slicing machine having a base, an article carriage reciprocally mounted on said base and a driven rotary cutter blade disposed adjacent said article carriage; the combination of an elongated housing spaced below and disposed in substantially parallel relation to the article carriage, said housing having spaced side walls, a pair of longitudinally spaced parallel wheels carried by each of said side walls, the wheels carried by one side wall being in substantially axial alignment with the respective wheels carried by the other side wall, a pair of closely spaced substantially parallel endless belts carried by the wheels, a pivot shaft spanning the distance between, and being carried by, adjacent reaches of the endless belts, a carriage propelling thrust shaft pivotally supported on said pivot shaft, means on said carriage for slidably supporting the upper end of said thrust shaft, a driving connection between the rotary cutter blade and at least one of the wheels on which each of the endless belts are mounted whereby said endless belts will impart reciprocatory movement to the article carriage, and manually operable means for disengaging the driving connection relative to the article carriage to facilitate manual reciprocation thereof.

7. In a slicing machine having a frame, a cutter blade carried by the frame and an article carriage reciprocally mounted on said frame; the combination of an auxiliary carriage spaced beneath the article carriage and being reciprocally mounted on said frame to move in parallel relation to the article carriage, at least one endless belt mounted adjacent the auxiliary carriage, a pivot pin carried by said endless belt, means for driving said endless belt, a carriage propelling shaft pivotally mounted on said pivot shaft and extending outwardly therefrom, a portion of said propelling shaft being longitudinally slidably mounted in said auxiliary carriage, a vertically movable plunger carried by said article carriage

and projecting downwardly therefrom and terminating in closely spaced relation to the upper surface of the auxiliary carriage, said vertically movable plunger having a notch in the lower end thereof, a pin projecting upwardly from the auxiliary carriage and adapted to fit in said notch, and manually operable cam means for raising and lowering said vertically movable plunger into and out of operative relationship with the pin carried by the auxiliary carriage to thereby facilitate mechanical and manual reciprocity of the article carriage.

8. In a slicing machine having a frame, a rotary cutter blade carried by the frame and an article carriage reciprocably mounted on said frame; the combination of a mechanism for mechanically reciprocating the article carriage comprising an elongated housing spaced beneath and extending in substantially parallel relation to the article carriage, said housing having spaced parallel side walls, a pair of longitudinally spaced parallel sprocket wheels rotatably supported by each of said side walls, an endless sprocket chain mounted on each of said pairs of sprocket wheels, a gear carried by one of the sprocket wheels of each pair, a shaft rotatably supported in said side walls, second gears fixed on said shaft and one each meshing with each of the first-named gears, a drive shaft disposed in axial alignment with the first-named shaft, means for continuously rotating the drive shaft, manually operable clutch means operatively connecting the first-named shaft with the drive shaft, a pivot pin carried by said endless sprocket chains and spanning the distance between corresponding reaches of said sprocket chains, a thrust shaft pivotally mounted adjacent one end thereof on said pivot shaft and extending upwardly therefrom, and means reciprocably connecting the thrust shaft with said article carriage whereby, upon said clutch means being operatively connected to the first-named shaft, said gear will impart rotation to the sprocket wheels and thereby move the sprocket chains, to, in turn, impart lateral reciprocatory movement to the thrust shaft and thus to the article carriage.

9. In a slicing machine having a frame, a cut-

ter blade carried by the frame and an article carriage reciprocably mounted on said frame; the combination of an auxiliary carriage spaced beneath the article carriage and being reciprocably mounted on said base to move in substantially parallel relation to the article carriage, at least one endless belt mounted beneath the auxiliary carriage, a pivot pin carried by said endless belt, means for driving said endless belt, a carriage propelling shaft pivotally mounted on said pivot shaft and extending upwardly therefrom, a portion of said propelling shaft being longitudinally slidably mounted in said auxiliary carriage, a substantially vertically movable plunger carried by said article carriage and projecting downwardly therefrom and terminating in closely spaced relation to the upper surface of the auxiliary carriage, said vertically movable plunger having a notch in the lower end thereof, a pin projecting upwardly from the auxiliary carriage and adapted to fit in said notch, spring means normally urging said plunger downwardly, said plunger having downwardly converging cam surfaces on its lower end adjacent opposite sides of said notch and manually operable cam means for raising and lowering said vertically movable plunger into and out of operative relationship with the pin carried by the auxiliary carriage to thereby facilitate mechanical and manual reciprocity of the article carriage.

HAROLD C. GROVE.
